(57) **CLAIM**

The ornamental design for the display for body composition analyzer, as shown and described.

DESCRIPTION

FIG. 1 is a right side perspective view of a display for body composition analyzer of my new design.

FIG. 2 is an enlarged view of the display of FIG. 1;

FIG. 3 is a front elevational view thereof.

FIG. 4 is a rear view of my new design;

FIG. 5 is a right-side view of my new design, the left side view being a mirror image thereof;

FIG. 6 is a top plan view of my new design;

FIG. 7 is a bottom plan view of my new design; and,

FIG. 8 is an enlarged front elevational view thereof.

The broken line showing is for illustrative purposes only and forms no part of the claimed design.
